SIGNALING SYSTEM AND CONTROL
THEREFOR

Samuel F. Arbuckle, Guy H. Coulter, and Charles E. Godley, Highland Park, Mich., assignors to United Lens Corporation, Detroit, Mich., a corporation of Delaware

Application March 26, 1937, Serial No. 133,258

6 Claims. (Cl. 177—337)

This invention relates to signaling systems for automotive vehicles and more particularly to means for controlling the operation of the indicating means used in said systems whereby the indicating means serve the dual purpose of producing warning signals and also directional signals.

The invention comprehends a circuit controlling means incorporated in the electrical system of an automobile using electro-responsive means for producing warning signals whereby the electro-responsive means are operated by the circuits controlling means to produce direction signals, and concurrently rendering the functioning of said electro-responsive means ineffective to produce warning signals.

The invention also embraces the provision of switching means for controlling the operation of the lamp circuits used as stop and tail-light signals whereby the same are rendered ineffective for a predetermined period of time and are concurrently used for producing directional signals.

One of the objects of the invention is to provide a switch associated with the circuits used for energizing a plurality of lamps so that when the switching means are in normal ineffective position the lamps produce stop and tail-light or other warning signals and when the switch is moved to operative position the lamps are energized to produce direction signals, rendering said stop and tail-light or other warning circuits ineffective.

Another object of the invention is the provision of a switching device for controlling a signaling system having means incorporated therein for causing the energization of the signals intermittently for a predetermined period of time, thus serving to indicate directional movements of a vehicle.

Another object of the invention is the provision of a switch having means to produce a periodic energization or flashing action for a predetermined period and the switch being provided with a removable element to render said flashing means ineffective.

Another object of the invention is to incorporate a switch having a delayed action subsequent to its actuation with the circuits normally used for energizing a plurality of lamps to produce stop and tail-light signals so that when the switch is actuated the lamps are so controlled as to produce direction signals, the switch rendering ineffective the normal use of the circuits for a predetermined period of time.

Another object of the invention is to produce 55

a switch including means for visually and audibly indicating to the operator or driver of a vehicle the proper operation of the system when direction signals are being produced.

5 A further object of the invention is to provide a compact switching means for controlling a directional signaling system operated by a single lever avoiding confusion to the vehicle driver in selecting the proper directional signal.

10 Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawings of a form of the invention, which may be preferred, in which:

20 Figure 1 is a side view of an automobile with a part broken away to show the application of the device of the invention;

25 Figure 2 is a rear view of an automobile using a pair of stop and tail-light signaling devices with which the invention has particular utility;

Figure 3 is a rear view of another form of direction signal devices with which the invention may be incorporated;

30 Figure 4 is a view similar to Figure 3 showing an automobile equipped with still another form of direction signal apparatus with which the invention may be incorporated;

Figure 10 is a fragmentary bottom plan view 50 showing the position of the switching means when moved to produce direction signals;

Figure 11 is a top plan view of the switch shown in Figure 5 with the casing being broken away to show the interior details;

Figure 12 is a sectional view taken substan-

tially on the line 12-12 of Figure 6 looking in the direction of the arrows;

Figure 13 is a diagrammatic view illustrating the circuit connections of one form of the invention showing a bottom plan view of the switching means;

Figure 14 is a diagrammatic view illustrating the circuit connections of another form of the invention.

Referring to the drawings in Figures 1 and 2, 10 an automotive vehicle 10 using a usual signaling system including two stop and tail-light indicating devices 12 and 14 is illustrated. The indicating devices 12 and 14 are secured to the left and right rear fenders 16 and 17 respectively 15 looking in the rear of the vehicle, and each device includes the light sources 18 and 20 preferably of different intensities to produce warning signals of different character. On terminal of each of the light sources is preferably grounded and the other is connected by suitable conductors to a source of current such as a storage battery B which also has one of its terminals preferably grounded to the frame of the automobile. The light source 18 which serves to produce a tail 20 light signal is controlled by means of the lighting switch 22.

The circuits for the energization of the light source 20 which serves to produce warning signals as well as direction signals are controlled by 30 normally open switches 23 and 25 actuated by the operation of the brake pedal 26 and the vehicle gear shifting level 28 respectively. In addition, the circuits for energizing the light sources 20 and 18 are also controlled by the switching means 35 of the invention preferably carried by the steering wheel column 31 located in convenient proximity to the steering wheel 32 so that the switching means of the invention can be actuated by the driver without removing the hand from the steering wheel.

The switching means of the invention including a clock mechanism used to produce a flashing and time delay action is enclosed by a casing 30. The casing 30 is mounted for vertical and lateral adjustment on steering wheel column 31 by means of bracket 33 and clamp 34 for the purpose of localizing it near the steering wheel 32. The bracket 33 is of channel shaped configuration serving to cover a portion of the conductors which connect the switching mechanism with the source of current and light sources.

The casing 30 is preferably made of insulating material, such as a phenolic condensation product or the like open at its back and comprises a narrow conduit portion terminating into a chamber 36 of hexagonal configuration. This chamber is of suitable dimensions for receiving and supporting a removable unitary assembly including the circuit controlling means and clock mechanism associated therewith.

This unitary assembly is carried by flat plates 40 and 41 of conducting material spaced apart and held in fixed relation by posts 42 and a removable plate 43 of insulating material is spaced from plate 41 and carried thereby, the plates 41 and 43 conform generally to the shape and dimensions of the hexagonal chamber 36 while plate 40 is preferably of smaller size and of a rectangular form as particularly shown in Figure 11. The clock mechanism and flashing means of the invention are supported between plates 40 and 41, while the various elements of the switch proper are mounted on plates 41 and 43. The plate 41 pivotally supports in direct contact 75

therewith a switch blade 44 made of current conducting material having a portion extending through an opening formed in the wall of casing 30 terminating into an insulating portion or manipulating handle 46. As shown in Figures 6 and 10 the switch blade 44 is pivotally mounted on a pin 45 fixed to plate 41 and is formed with a reduced end portion 47, contacting section 48 and a camming portion 49 adjacent to the pivotal point. The contacting section 48 is adapted to engage either of the relative stationary spring contact members 50 and 51 insulatingly mounted and supported by plate 41, and section 48 is of a width that it can not be simultaneously placed in engagement with both contact members 50 and 51, and therefore the switch arm can take the central neutral position shown in Figure 6 or moved by handle 46 to the right or left to the positions as illustrated in Figure 10 for establishing predetermined circuits with either contacts as will hereinafter appear.

As particularly shown in Figure 6, the stationary contacts 50 and 51 are formed with integral projections or bus bars 52 and 53 also insulated from conducting plate 41. The bus bars 52 and 53 are adapted to engage the base terminals of a light source or light bulb 55 acting as a tell-tale device removably carried by projection 38' of casing 30. The light bulb 55 as particularly shown in Figures 11 and 12, is enclosed by a removable translucent cover 57' of suitable material which protects the light bulb from damage and is preferably of a color to project a suitable colored light to give when the light source is energized a definite tell-tale indication to the driver.

The flat plate 43 of insulating material (see Figure 10) carries on its inner face and in close proximity thereto a movable conducting blade 57 pivotally mounted as at 58 and provided with an opening or slot 60 adapted to receive a pin 62 of insulating material secured to switch blade 44 acting as connecting means therebetween. The blade 57 is formed with a raised portion 63 adapted to be simultaneously engaged by contacting fingers 65 and 66 projecting through a slot 68 formed on plate 43. Fingers 65 and 66 form integral parts of arms 69 and 70 carried on the outer face of plate 43, and are secured thereto by means of rivets 71 and 72 which also serve to connect these arms to each of the conducting plates 73 and 74 carried on the inner surface of flat plate 43. The switch blade 57 is connected to a plate 76 also carried on the inner face of plate 43. The ends of each of the conducting plates 73, 74 and 76 are formed with suitable openings coinciding with spaced openings formed in the insulating plate 43.

The openings formed in the conducting plates 73, 74, 76 coinciding with openings formed in insulating plate 43 as well as opening 81 formed on the latter are adapted to accommodate the reduced ends of metallic posts 77, 78, 79 and 80 insulatingly carried by plate 41 which are formed with suitable shoulders for locating the plate 43 in spaced relation to plate 41. The plate 43 is removably held in position by means of screws 83, 84, 85 and 86, which are received in threaded openings formed on the end of each post. The screws 83 to 86, inclusive, serve as circuit terminals and means for securing conductors to the different elements of the switching mechanism. The screw 83 on post 77 serves as a connecting terminal for contact 50, the bus bar 52 and finger 65 through plate 73 and arm

69. The screw 86 acts as a terminal for establishing a connection to contact 51, bus bar 53 and finger 88 through plate 74 and arm 10. The screw 84 serves as a terminal to establish a connection to movable blade member 87 through plate 76 contacting therewith. The screw 85 serves as means for establishing a circuit through post 78 to a spring contact 88 forming part of the flashing mechanism insulatingly mounted on the inner face of plate 41 as shown in Figure 12. The screw 85 serves to removably support on the outer face of plate 43 a conducting arm 89 provided with a depending member or contact piece 90 passing through openings formed on plates 43 and 41 preventing any contacting engagement with conducting plate 41 as particularly shown in Figure 7. The contact piece 90 is adapted to engage and flex conducting spring 91 forming a component part of a fuse receiving clamp 93 which serves with a spaced clamp 94 to removably hold in position a suitable fuse 92, provided with a terminal 95 to which is adapted to be connected a conductor 96 directly connected to one terminal of the storage battery or source of energy, as particularly shown in Figure 13.

The manipulating handle 46 operates when moved to the right or left to open and close the circuits controlled by the switch blades 44 and 57 and also the initiation of the timing train which serves to cause a flashing action of the circuit and determines the period of time during which the circuits are operative or inoperative. The apparatus thus far described constitutes the electric switching means proper of the invention. As forecasted, automatic timing means are provided for returning the switch to off position automatically, once it has been manually actuated to on position. The particular construction and arrangement of the time train and flashing means is fully disclosed and described in detail in our co-pending application Serial No. 125,712, filed February 15, 1937, now Patent No. 2,230,994 with this application and therefore for the purpose of describing the present invention only the essential parts are illustrated and described.

As shown in Figure 6 plate 41 is formed with curved slots 102 and 103 to permit the oscillatory movement of the projections 104 and 105 which extend therethrough and are adapted to be engaged by the opposite side walls of portions 47 and 48 of movable switch arm 44 for the purpose of winding the clock mechanism when the handle 46 is moved and for returning automatically the switch arm 44 to central position after a predetermined time has elapsed.

As shown in Figures 12 and 6 the projections 104 and 105 form an integral part of a control switch trip bar 106 the same being fixedly carried by the rotatable shaft 107, which is journaled between plates 40 and 41. Fixedly secured to shaft 107 for rotation therewith is clutch disc 110 and spring tensioning disk 111. Between disks 110 and 111 is loosely mounted on shaft 107 for rotation relative thereto a bushing 112 and main gear 113 the latter being of usual construction and formed with suitable means to be engaged by the clutch disk 110 forming a one way driving clutch between clutch disk 110 and main gear 113, the driving connection being present when the clutch disk 110 is moved under the tension of a coil spring 118 located around member 107 between frame plate 40 and tensioning disk 111. The coil spring 118 has one end 75

engaging the projection 119 forming an integral part of disk 111 and its other end retained by one of the struck-up projections or ears 120 formed on plate 40. Plate 40 as particularly shown in Figure 11, is formed with a plurality of struck-up projections or ears 120 for the purpose of providing means to adjust the tension of spring 118.

As particularly shown in Figures 11 and 12, a gear train and an escapement mechanism associated with the main gear 113 for the purpose of permitting the energy produced by the tensioning of spring 118 to expend itself at a predetermined rate of speed as well as serving the circuit flashing means, consists of the pinion 122 in mesh with gear 113 and mounted on shaft 123 which also carries a larger gear 124 and a flash wheel 126, the latter having teeth or contacting projecting surfaces 128 which when rotated are adapted to be engaged by the spring contact 88 to produce a flashing action.

The gear 124 is in mesh with a pinion 134 mounted on a shaft 135 which also carries a gear 136. The gear 136 is in engagement with a pinion 137 mounted on a shaft 138, which also carries a toothed wheel 139. A flutter wheel 140 provided with pins 141 and 141' adapted to engage alternately the teeth of the wheel 139 is mounted on a balance shaft 142 pivoted on adjustable bearings mounted on plates 40 and 41. The movement of the gear train which is caused by the unwinding action of the spring 118 is timed by the action of the flutter wheel 140 which oscillates by the rotative action imparted on the pins 141 and 141' by teeth of wheel 139, allowing with each oscillation the passage of one tooth of the wheel 139 to cause its timed intermittent motion; the arrangement not only serving as escapement mechanism but also producing a distinct audible sound or buzzing action for the purpose of indicating that the gear train is in operation. The projection or lug 119 of the spring tension disc 111 as shown in Figure 12 serves as a stop means for the gear train when the switch blade 44 is in central position by engaging a projection 128 of the flash wheel 126. However, when the manipulating lever 46 is moved to the right or left winding up spring 118, the spring tension disc 111 is rotated moving the lug 119 out of engagement with the projection 128 permitting the rotation of the gear train for a predetermined time until the lug 119 once more engages one of the projections 128 of the flash wheel 126 thus stopping the gear train.

The circuit connections as well as the switching means for the form of the invention shown in Figure 1 are particularly illustrated diagrammatically in Figure 13 wherein a bottom plan view of the switching means is shown, the signaling systems including the use of the devices to produce stop and tail-light warning signals, where it can be seen that the storage battery B grounded as at 16 has its other terminal connected by conductor 96 including fuse 92, contact piece 91, arm 89 through screw 85 and post 79 to the spring contact 88 of the flashing means of the invention. Considering the circuit for the left side signaling device, the stationary switch contact 50, bus bar 52 for one of the tell-tale base terminals as well as contacting finger 65 for the stop signal which are connected to switch terminal 83 are connected through conductor 145 to a terminal of the light source 20 carried by signaling device 12 located on the left side of the vehicle. The light source 20 had its other ter-

terminal grounded as at 148 forming a ground return to the battery B. Considering the circuit for the right side signaling device, the stationary switch contact 51, bus bar 53 for the other tell-tale base terminal as well as contacting finger 68 for the stop signal which are connected to switch terminal 86 are connected by conductors 148 to a terminal of the light source 20 carried by signaling device 14 located on the right side of the vehicle, this light source having its other terminal grounded at 149. The switch blade 57 mounted on the insulating plate 43 connected by plate 16 to switch terminals 84 is connected by means of a lead 150 to the stationary contact 151 of stop switch 23. The stop switch terminal 152 is connected to the switch blade 153 adapted to engage the stationary contact 151 by the movement of the brake pedal 26 to brake applying position. The stop switch terminal 152 is connected by lead 155 to the conductor 96 which in turn is connected to the live terminal of storage battery B.

Connected to the stop switch terminal 152 and stationary contact 151 are the terminals 157 and 159 of the back-up switch 25 which are adapted to be bridged by contacting member 160 when the gear shift lever 28 is moved to a position in which a rearward motion is imparted to the vehicle. The light sources 18 located in signaling devices 12 and 14 serving as tail-light, warning signal and license plate light are grounded as at 162 and are connected by means of leads 163 and 165 to lighting switch terminal 166 while lighting switch blade 167 is connected by lead 168 to a conducting arm 170 carried on the outer face of insulating plate 43 and having a portion passing through the plate slot 173 terminating into a contacting finger 175 adapted to contact with projection 47 of switch blade 44 when the same is in its central position. Suitably spaced from finger 175 is a finger 176 contacting with projection 47 of switch blade 44. The contacting finger 176 forms part of conducting arm 178 supported on the outer face of plate 43 the arm 178 having a portion passing through slot 173. The conducting arm 178 is connected by lead 180 to conductor 96 and hence to the live terminal of the battery.

The operation of a form of the invention constituting the signaling system hereinbefore described can be summarized as follows: If the driver of the vehicle desires to make a left hand turn it will only be required to move the switch operating handle 46 to the left so that the switch lever is moved in the same direction as the proposed vehicle turn and will be located on the position identified by the words "Left" appearing on the top face of the switch casing 30. It should be noted that Figure 13 shows the switching means in upside down position and therefore the direction of movement there indicated appears opposite to the actual movement of the lever in use.

When the switch handle 46 is moved to "left" position as shown in Figure 10 the switch blade 44 is moved into engagement with stationary contact 50 and the movable blade 57 is rotated by the movement of blade 44 to a position where the same is out of contacting engagement with fingers 65 and 66 preventing the flow of current to both light sources 20 that can be normally established by closing stop switch 23 caused by the movement of the brake pedal 26 to brake applying position. In addition the movement of switch blade 44 to the position shown in Figure 10 winds

up the main spring 118 by moving the projection 104 of the trip bar 106 rotating thereby shaft 107 and clutch disc 110 independent of gear 113 and concurrently moving the lug 118 of the spring disc 111 out of engagement with the teeth 128 on the flash wheel 126. When this movement is completed the gear train will start its rotation due to the force stored by the winding up of spring 118 as the clutch disc 110 will drive the main gear 113, rotating the flashing gear 126 and causing teeth 128 to engage the spring contact 88. The contacting engagement of spring 88 with flash wheel teeth 128 provides a circuit for the flow of current to the light source 20 in device 12. This circuit comprises flash wheel teeth 128, switch plate 41, switch blade 44 in electric contact with plate 41 and in engagement with stationary contact 50 which is connected through switch terminal 83 by means of conductor 145 to light source 20 of the left signaling device 12.

The rotation of flash wheel 126 by the gear train produced by the unwinding action of spring 118 will close and open the circuit to the left light source 20 on device 12 by the periodic engagement of flash wheel teeth or contacting projections 128 with spring contact 88 causing the intermittent energization of the light source 20 of the left signaling device 12 producing light flashes of very short duration attracting the attention of observers giving a warning that the driver is intending to impart a left hand turn to the vehicle. This flashing action will be present for a predetermined period thus giving a warning signal before and during the time required to effect the turning of the vehicle.

It is important to note that when the switch is in the left signaling position and during the periods of time that stationary spring contact 88 of the flashing means which is directly connected to the battery, is in engagement with any of the flash wheel contacts 128 producing the momentary energization of the light source 20 of device 12 forming the left directional signal, the tell-tale 55 is also energized by a branch parallel circuit established and controlled by switch blade 44. This branch parallel circuit includes the switch blade contacting section 49 in engagement with contact 50 and by means of the bus bar 52 to the terminal of tell-tale 55 in engagement therewith and from the other tell-tale light terminal by means of bus bar 53 to terminal 86 connected by conductor 148 to light source 20 of the opposite or right signaling device 14 which is grounded at 149 providing a return to battery B.

From the foregoing it can be seen that when this branch parallel circuit is established while a left directional signal is being produced the light filament of the tell-tale device 55 and the filament of the light source 20 located in the opposite or right hand positioned signaling device 14 are connected in series. However due to the total resistance of the branch parallel circuit the current flowing is only sufficient to energize the tell-tale 55 and not the light source 20 connected in series therewith. The energization of the tell-tale 55 will produce light flashes indicating to the driver that a direction signal is being produced.

In this embodiment of the invention, in order to produce a direction signal very reliable for day or night operation eliminating the possibility that drivers cannot clearly distinguish the light flashes caused by the energization of light sources 20 when direction signals are produced, the en-

nergization of the tail-lights 18 is not solely effected by the closing of lighting switch blade 167 but it is also controlled by the switch blade 44. The control is such that when the blade 44 is moved to produce direction signals, the circuit for the flow of current to the tail-light switch blade 167 is open. This is caused by moving the end portion 47 of switch blade 44 from contacting engagement with spaced fingers 175 and 176. However, this circuit control for the tail-light signals is normally closed when the switch blade 44 is in its central position as the end portion 47 engages both contacting fingers 175 and 176 whereby the closing of switch blade 167 fully controls the light sources 18 to produce tail-light signals. Moreover the switch blade 44 serves to re-establish the energization of the light sources 18 whenever the same are energized prior to the production of direction signals particularly at night when the switch blade 167 is in closed position.

The unwinding action of spring 118 causes the switch blades 44 and 57 to be slowly moved back toward their central position by the rotation of projection 104 of trip bar 106 which is in contact with the end portion 47 of the switch blade 44, and will cause, first: to interrupt the contacting engagement of switch blade contacting portion 49 with stationary contact 50 causing the breaking of the circuit established for energizing the left positioned light source 20, as well as the circuit of the tell-tale 55, and second: to move the raised portion of switch blade 57 into engagement with contacting fingers 65 and 66 thereby rendering effective the stop switch control for light sources 20, and third: to move the switch blade 44 to its central position causing the bridging engagement of contacting fingers 175 and 176 with the switch end portion 47 to render effective the control of light sources 18 by tail-light switch blade 167, and simultaneously causing the engagement of projection 119 with a tooth 128 of wheel 126 to stop the gear train whereby the switch blade 44 and associated parts are placed in the position shown in Figure 6. In the embodiment shown, the return action to central position of blade 44 to break the circuit established for energizing the left light source is timed through the gear train and escapement mechanism to require a period of approximately 15 seconds, a period long enough to complete the average turn, and during this length of time the left hand positioned light source 20 is intermittently flashed by the periodic engagement of teeth 128 of flashing wheel 126 with spring contact 88.

When engagement between projection 119 and teeth 128 takes place, the spring contact 88 is out of engagement with any of the flashing wheel teeth 128, so that when the switch blade 44 is in a central position no current is passing to the light sources 20 or tell-tale 55 through the flash wheel 126.

Heretofore we have been describing the operation in connection with a left hand turn. The operation in connection with a right hand turn will now be described. If the driver of the vehicle desires to indicate his intention to make a right hand turn the switch handle 46 is moved to the position identified in the switch casing by the word "right" wherein the switch contacting portion 49 is in engagement with contact 51 to energize the light source 20 located on signaling device 14 through conductor 148 to produce a flashing action, warning observers that a turn to the

right is going to be made by the vehicle. The movement of switch blade to the right will cause: the engagement of switch blade portion 48 with trip bar projection 105 to rotate shaft 107, moving the projection 119 out of engagement with the flash wheel teeth 128 and winding up spring 118 to impart rotating torque to gear 113; it will also cause the projection 47 of switch blade 44 to be moved out of engagement with the contacting fingers 175 and 176 rendering the control of the tail light sources 18 by the tail-light switch blade 167 ineffective; and in addition this movement will serve to rotate the switch blade 57 moving it from contacting engagement with fingers 65 and 67 rendering the control of the light sources 20 by the stop and back-up switches ineffective.

After the movement of the switch blade 44 to the right is completed the torque action of spring 118 is transmitted to the gear 113 to start the rotation of the gear train whereby the flash wheel teeth 128 are moved into engagement with spring contact 88 causing the light source 20 located on the right signaling device 14 to produce lighting flashes of very short duration warning that a right hand turn is going to be imparted to the vehicle. The energizing circuit to the light source 20 in the right hand device 14 includes the flash wheel teeth 128 through switch plate 41 to switch blade 44 in contacting engagement with stationary contact 50 connected to switch terminal 86 and through conductor 148 to the light source 20 on signaling device 14. When the right hand light source 20 is energized the tell-tale 55 is also energized to give a flashing visual indication that a direction signal is being produced as a branch circuit is established in parallel with the right hand light source. This parallel branch circuit includes the switch blade contacting section 49 in engagement with stationary contact 51 through bus bar 53 to the terminal of tell-tale 55 in engagement therewith and from the other terminal of the tell-tale by means of bus bar 52 to terminal 83 connected by conductor 145 to the light source 20 of the opposite or left signaling device 14. Due to the fact that light sources 20 and 55 are connected in series the current flowing in this branch parallel circuit is only sufficient to energize the tell-tale 55 to produce intermittent flashes.

The unwinding action of spring 118 will cause the switch blades 44 and 57 to be slowly moved back to their respective central positions, this movement being caused by the engagement of trip bar projection 105 with portion 48 of the switch blade 44. This movement will serve to open the circuit established for the energization of the light source 20 located in the right hand signaling device 14 and to stop the gear train by moving projection 119 into engagement with a tooth 128 of the flash wheel 126. When the gear train is stopped the projection 47 will be placed in engagement with fingers 175 and 176 rendering the control of tail-light sources 18 by the switch blade 167 effective. In addition, the projection 63 of the switch blade 57 will be in engagement with contacting fingers 65 and 66 rendering the control for both of the light sources 20 by the stop and back-up switches effective. It is important to note that this form of the invention includes means giving audible and visual indications during the period of time that the signaling system operates to give direction signals so that the driver is aware that a direction signal is produced while turning the vehicle and should

these indications cease before the turning operation is completed it will only be necessary to move again the switch handle 46 to the proper position. In addition, the switch blade 44 is so connected with trip bar 106 that the switch blade can be moved instantly to the right or left positions changing immediately the energization of either the right or left light sources 20 without interfering with the time element required to move the switch blade 44 to its central or circuit open position.

In Figure 3 we have illustrated a modification in which the switch means of the invention including the clock mechanism used to produce the flashing and time delay action hereinbefore described can be effectively used to control the actuation of direction signaling devices of the type shown in Figure 3 which consists of a right-turn indicating arrow 180 and a left-turn indicating arrow 182 which are illuminated by independent light sources to produce a visual indication when a right hand turn or a left hand turn is going to be imparted to the vehicle. When this type of directional signals is used in association with the switching means of the invention, it is only necessary to connect terminal 83 of the switching device to the light source associated with the left hand indicating arrow and the switch terminal 86 to the light source associated with the right hand indicating arrow and connecting the live terminal of the storage battery to the fuse terminal 95, no other connection being established with the remaining terminals of the switch device as in this case it is not necessary to modify in any way the energization of the stop and tail-light signals. It can be seen that movement of the switch manipulating hand 46 to right or left will serve to energize and cause the flashing of the light sources to indicate that the desired turn is going to be imparted to the vehicle, the gear train in this case automatically returning the switch blade 44 to the normal central position interrupting the energization of the light source, the flashing means functioning during the period of connection to produce flashes of short duration in the circuit of the light source energized by the actuation of the switch blade, and at the same time causing the energizing tell-tale 55 to produce light flashes indicating the operation of the direction signals.

The switching means of the invention including the clock mechanism as hereinbefore pointed out is provided with removable means for rendering the flashing action ineffective for the purpose of adapting the switch means to control directional signals of the type wherein the flashing action of the switching means is not desirable. Such an arrangement is shown in Figures 4 and 14.

Referring to the drawings, Figure 4 illustrates the signaling device 184 located in the right hand fender of an automobile of the type with which the flashing action of the switching means is not desirable. The signaling device illustrated consists generally of arrows 186 and 187 moved to different positions by electric responsive means or other operative means electrically controlled. The arrow 186 is adapted to be rotated counter-clockwise for the purpose of indicating a right hand turn as particularly shown in Figure 4, and the arrow 187 adapted to be moved clockwise to indicate a left hand turn as particularly shown in dotted lines in Figure 14. Associated with arrows 186 and 187 are suitable light sources having one terminal usually grounded. The light

sources are adapted to be simultaneously energized when the arrows are moved to direction indicating positions for the purpose of enhancing the visibility of the signal.

The flashing means may be eliminated as will be noted by examination of Figures 7 and 9 where it will be seen that when the conducting arm 89 is removed from the switch mechanism the spring element 91 normally flexed and in contact with depending member 88 moves automatically to the position shown in Figure 9 wherein the spring element 91 engages the conducting plate 41 of the switch member establishing a direct circuit connection from terminal 95 through fuse 92 to plate 41 in direct contact with the switch blade 44. The contacting engagement of spring 91 with plate 41 disconnects the spring contact 88 from the switch terminal 95 so that its contacting engagement with the flash wheel teeth 128 does not affect in any way the flow of current to switch blade 44. Thus the flashing action of the switching mechanism is placed out of commission by the removal of member 88 which can be accomplished by removing the screw 78 which serves to hold the arm 89 in position.

Figure 14 shows the effective circuits that can be established by the movement of the switch blade 44 when the spring 91 is in direct engagement with conducting plate 41. The wiring diagram of connections here illustrated includes a storage battery having one terminal grounded as at 190 and having its other terminal connected by lead 192 to the fuse contact 95 which as hereinbefore explained through fuse 92 and spring element 91 connects the switch blade 44 through plate 41 with the fuse terminal 95. As herein illustrated, the terminal 86 of the switching means of the invention is connected by means of lead 193 to the arrows 186 adapted to indicate when energized a right hand turn of the vehicle, the contact 83 in this instance being connected through lead 194 to the arrows 187 which are adapted to indicate a left hand turn when the same are energized. It can be seen that movement of the switch blade 44 to the left will establish a circuit connection to the operative means that serve to actuate the arrows 187 whereby the same are moved to the position illustrated in dotted lines in Figure 14 and simultaneously will cause the energization of the light sources associated therewith.

In this embodiment of the invention illustrated in Figure 14, the actuation of the switch manipulating handle 46 to the left imparted by the driver to give a signal indicating that a left hand turn is going to be imparted to the vehicle will wind the spring 118 and start the gear train to provide the time period during which the left direction signal is in operation before the switch blade is moved automatically to central position. In addition, the engagement of the movement of the switch blade to the left position will cause the energization of the tell-tale 55 by establishing a circuit wherein the tell-tale 55 is in a series connection with the operative means of the arrows 186. The flow of current in this series circuit is such that it is only sufficient to energize the tell-tale 55 but ineffective to cause the movement of the arrows 186, thus the tell-tale 55 is energized during the period of time that the switch means are in operation, thereby providing means to advise the driver that a direction signal is being produced.

In this embodiment it should be understood that movement of the switch handle 46 to the

"right" position by the driver to indicate a right hand turn will produce the energization of the right turn indicating arrows 186, and the simultaneous energization of the tell-tale 55, providing by the actuation of the gear train a sufficient time to effect the turning of the vehicle prior to the interruption of the flow of current to the arrows 186, by the returning of switch blade 44 to central position. It should be noted that the gear train associated with the switch blade 44 is not affected in any way by the removal of the conducting arm 89 and that the same only changes the effective connections to the flashing means of the invention.

It is apparent that, within the scope of the invention, modifications and different arrangements may be made other than is herein disclosed, and the present disclosure is illustrative merely, the invention comprehending all variations thereof particularly wherein the illuminated direction signal is visually effective independently of other warning signals.

What we claim is:

1. A combination direction and stop signaling system for automotive vehicles, a pair of spaced lights located at one end of a vehicle respectively positioned at each side of the central vertical plane of the vehicle for giving vehicle direction and stop signals; connections between each of said lights and a source of electrical energy; switching means for said connections including a selector contacting element having a central position and movable to opposite operative positions for selectively establishing a circuit through said connections from the source of electrical energy to each of said lights; a mechanism including a periodic circuit interrupter rendered operable by the manual movement of said selector element from its central to one of said operative positions for fluctuating the current flow through the selectively connected light to flash the same intermittently to thereby indicate a vehicle turn signal; means engageable with the selector contacting element actuated by said mechanism for returning said selector contacting element from its operative to its central position and for maintaining said selector contacting element in said operative position for a predetermined number of flashes of light; additional circuit closing means intercalated with said connections for establishing simultaneously a continuous flow of current to both of said lights when said selector element is in its central position indicating thereby a stop signal, the circuit closing means being so arranged that when said selector contacting element is in any of its operative positions the continuous flow of current to said lights is rendered ineffective.

2. In a signal circuit organization for vehicles including a normally open switch; a second switch normally open; a circuit closer manually movable from a neutral position to two operative positions; a pair of signal lamps mounted on the rear on the opposite sides of the center of the vehicle each having a pair of energizable filaments; current conducting means including the circuit closer in its neutral position whereby the closing of said first mentioned normally open switch simultaneously and constantly energizes one of the filaments in both signal lamps from a current source to produce a stop signal; current conducting means including the circuit closer in its neutral position whereby closing of the second normally open switch simultaneously and constantly energizes the second filament in both

5 signal lamps to produce a tail light signal; a mechanism set into actuation by the manual movement of the circuit closer for intermittently energizing a single filament of a single signal lamp to indicate a vehicle turn; means operable by said mechanism for returning the said circuit closer after a predetermined period of time to its neutral position; and contacting means engageable with the circuit closer for rendering the energization of the filaments by said switches ineffective when said circuit closer is moved to either of its operative positions.

3. A combination direction and warning signaling system for motor vehicles; a plurality of spaced illuminating means located at one end of the vehicle, said means including electrically energizable filaments for giving a flashing vehicle directional signal and a steady warning signal; connections between each of said filaments and a source of electrical energy; switching means for said connections including a selector contacting element having a neutral position and manually movable to operative circuit closing positions for selectively establishing a circuit connection for energizing one of the filaments to indicate direction of the vehicle turn; means including a periodic circuit interrupter operable in response to the setting of said selector element in any of the operative positions thereof for fluctuating the current flow through the selectively connected filament to flash the same intermittently to thereby indicate a turn signal; means cooperating with the switching means for temporarily maintaining said element in circuit closing position and for automatically returning said selector contacting element from an operative to its neutral position to open the circuit established by said selector contacting element after the turning of the vehicle has been effected; additional switching means for permitting the establishment of a steady flow of current to a filament, said switching means being movable to a closed circuit position to permit the indication of a warning signal; each of said filaments in said illuminating means and said circuit establishing means being so arranged that when said selector contacting element is in any one of its operative positions an illuminated flashing directional signal is visually effective independently of the position of said additional switching means.

4. In a signal circuit for motor vehicles; a plurality of spaced electrically energizable filaments including spaced flashable filaments located at one end of the vehicle; connections between each of said filaments and a source of electrical energy; switching means including signal selector means having a neutral position and manually movable to operative circuit closing positions for selectively establishing a circuit connection for energizing one of the filaments to indicate direction of the vehicle turn; a periodic circuit interrupter operable in response to the setting of said selector means in any of the operative positions thereof for fluctuating the current flow through the selectively connected filament to flash the same intermittently to thereby indicate a turn signal; means cooperating with the switching means for temporarily maintaining said selector means in circuit closing position and for automatically returning said selector means from an operative to its neutral position to open the circuit established by said selector means after the turning of the vehicle has been effected; additional circuit closing means for

establishing a steady flow of current to a non-flashable filament when said selector means is in its neutral position indicating thereby a warning signal; each of said filaments in said illuminating means and said circuit establishing means being so arranged that when said selector means is in any one of its operative positions an illuminated flashable directional signal filament is visually effective independently of the position of said additional circuit closing means.

5. A combination direction and warning signaling system for motor vehicles; a plurality of spaced illuminating means located at one end of the vehicle, said means including electrically energizable filaments for giving a flashing vehicle 10 directional signal and a steady warning signal; connections between each of said filaments and a source of electrical energy; switching means for said connections including a selector contacting element having a neutral position and manually movable to operative circuit closing 15 positions for selectively establishing a circuit connection for energizing one of the filaments to indicate direction of the vehicle turn; means including a periodic circuit interrupter operable 20 in response to the setting of said selector element in any of the operative positions thereof for fluctuating the current flow through the selectively connected filament to flash the same intermittently to thereby indicate a turn signal; means cooperating with the switching means for temporarily maintaining said element in circuit closing position and for automatically returning said selector contacting element from an operative 25 to its neutral position to open the circuit established by said selector contacting element after the turning of the vehicle has been effected; additional circuit closing means for establishing a steady flow of current to a plurality of filaments when said selector element is in its neutral position indicating thereby a warning signal; each of said filaments in said illuminating means and said circuit establishing means being 30 so arranged that when said selector contacting element is in any one of its operative positions an illuminated flashable directional signal is visually effective independently of the position of said additional circuit closing means; tell-tale means and connections therefor; said tell-tale means and connections being so arranged 35

with said filaments and periodic circuit interrupter that said tell-tale means gives a flashing indication only when said selector contacting element is in any one of its operative positions upon the production of vehicle direction 40 flashing signals.

6. In a signal circuit for motor vehicles; a plurality of spaced electrically energizable filaments including spaced flashable filaments located at one end of the vehicle; connections between each of said filaments and a source of electrical energy; switching means including a signal selector means having a neutral position and manually movable to operative circuit closing positions for selectively establishing a circuit connection for energizing one of the filaments to indicate direction of the vehicle turn; a periodic circuit interrupter operable in response to the setting of said selector means in any of the operative positions thereof for fluctuating the current flow through the selectively connected filament to flash the same intermittently to thereby indicate a turn signal; means cooperating with the switching means for temporarily maintaining said selector means in circuit closing position and for automatically returning said selector means from an operative to its neutral position to open the circuit established by said selector means after the turning of the vehicle has been effected; additional circuit closing means for establishing a steady flow of current to a non-flashable filament when said selector means is in its neutral position indicating thereby a warning signal; each of said filaments in said illuminating means and said circuit establishing means being so arranged that when said selector means is in any one of its operative positions an illuminated flashable directional signal filament is visually effective independently of the position of said additional circuit closing means; tell-tale means and connections therefor controlled by said signal selector means; said tell-tale means rendered effective for operation only when said signal selector means is in one of its operative circuit closing positions whereby the production of direction flashing signals renders said tell-tale means operative.
